United States Patent Office

MOSES G. WILDER, OF WEST MERIDEN, CONNECTICUT.

Letters Patent No. 65,143, dated May 28, 1867.

IMPROVEMENT IN PUNCHING-PRESSES.

The Schedule referred to in these Letters Patent and making part of the same.

TO ALL WHOM IT MAY CONCERN:

Be it known that I, MOSES G. WILDER, of West Meriden, county of New Haven, and State of Connecticut, have invented certain new and useful Improvement in the Manufacture of Presses, for working metal, &c.; and to enable others skilled in the art to make and use the same, I will proceed to describe by referring to the drawings, in which the same letters indicate like parts in each of the figures.

The nature of this invention will be understood from the specification and drawings.

The object desired to be attained thereby is, to so arrange the mechanism that by simply turning a spiral wheel the upper and lower dies may be easily and quickly adjusted to their proper relative positions with each other. In the accompanying drawings—

Figure 1 is a side elevation of this invention.

Figure 2 is a detached view of the adjusting device, by means of which the relative working position of the dies is regulated.

A is the stock of the press. B is the bed of the press, in or upon which the dies are arranged for use, and to which the stock is united and supported. C is a socket, which forms part of the stock, in which the shaft D is arranged, and operates the upper die, much in the usual way. The head A' of the stock A is provided with an opening, in which the lever E is arranged so as to work closely and freely therein. This lever is secured within said opening upon an eccentric pin, F. The eccentric pin F (see fig. 2) is made in the form of a bolt, having a head and nut for securing it in its proper place. This pin or bolt is provided with an eccentric wheel, larger in its diameter than the diameter of the bolt. Said eccentric is secured on said bolt by means of a key, a, or its equivalent, and in such a position that it may be easily revolved with the motion of the pin between the sides of said opening in the head A'. The lever E is mounted upon said eccentric pin so that the centre of its action or movement may be elevated or depressed by the relative position of said eccentric G with its pin F. The front end of this lever, E, is provided with a slit or opening (shown by dotted lines through the shaft D) through which the pin i passes to connect the lever E with the shaft D. In order to effect a movement or partial revolution of the eccentric, a gear, H, is made or secured on the outer or head end of the pin F. I is a spindle secured in bearings in the bosses I', (formed on the sides of the head A'), in a right-angled position with the pin F, or nearly so. Upon this spindle, and between the bosses I', is secured a spiral or worm-wheel J, so that it will work into the gear H, to turn the eccentric more or less into any given or required position, to elevate or depress the centre of the lever E at fulcrum. Thus by turning the spindle I the wheel J will act upon the gear H and turn the eccentric more or less as may be required. K is a foot-treadle lever, secured to the frame or stock of the machine by a bolt or pin, c. This treadle is provided with a stop-eatch, d, which strikes against or upon the boss d', thus fixing the extent of its downward motion. When the treadle K is depressed and the shaft D is elevated to their proper resting place, the length of the connecting-rod or arm L is ascertained, and is secured by bolts or pins e at or near the ends of said lever and treadle. The dies are arranged to the shaft D and bed B in the usual way. Now, after the dies have been properly arranged, and it is desirable to adjust the action of the upper die with the lower die, it is only necessary, first, to place the foot upon the treadle, and with one hand turn the spindle I until the action of the eccentric upon the lever shall elevate or depress the die to produce the desired relative position with each other, thus saving a great amount of time and irksome labor, and rendering the machine more desirable and convenient for use. I believe I have thus shewn the nature, construction, and advantage of this improvement, so as to enable others skilled to make and use the same therefrom.

I claim the combination of the eccentric G, stock A, shaft B, lever E, arranged and operating substantially as described.

I claim the combination of the eccentric G, stock A, shaft D, levers E K, arm L, with the wheel H J, substantially as and for the purpose described.

MOSES G. WILDER. [L. S.]
